UNITED STATES PATENT OFFICE.

GEORGE D. KINSEY, OF BROOKLYN, NEW YORK, ASSIGNOR TO THE AUSTRALIAN KNITTING COMPANY, OF PATERSON, NEW JERSEY.

DESIGN FOR A KNITTED FABRIC.

SPECIFICATION forming part of Design No. 19,097, dated May 14, 1889.

Application filed April 12, 1889. Serial No. 307,033. Term of patent 7 years.

To all whom it may concern:

Be it known that I, GEORGE D. KINSEY, of Brooklyn, in the county of Kings and State of New York, have invented and produced a new and original Design for Knitted Fabrics, of which the following is a specification.

The accompanying drawing illustrates a design embodying my invention, the design being shown in the black portions of the figure.

The design consists, essentially, of substantially zigzag figures A, arranged near opposite edges of the design. Intermediate of the zigzag figures A are substantially cup-shaped

figures B. Extending downwardly from the 15 cup-shaped figures B are stem-like portions C, and extending upwardly from within the cup-shaped figures B are substantially cone-shaped figures D. Outside the cup-shaped figures B are substantially dot-like figures a. 20

What I claim as my design is—

The design for knitted fabrics, substantially as herein shown and set forth.

GEORGE D. KINSEY.
